MASSACHUSETTS.

SPARKING DEVICE.

947,155.

Specification of Letters Patent. Patented Jan. 18, 1910.

Application filed March 3, 1909. Serial No. 481,086

To all whom it may concern:

Be it known that we, ISAAC W. GILES and CHARLES W. TOBEY, citizens of the United States, and residents, respectively, of New Bedford and Fairhaven, in the county of Bristol and State of Massachusetts, have made certain new and useful Improvements in Sparking Devices, of which the following is a specification.

Our invention relates to means for generating a current of high potential for use in connection with a sparking device such as is commonly used in explosive engines, and it consists in the combinations, constructions, and arrangements herein described and claimed.

An object of our invention is to provide a circuit breaker on an induction coil which will give one large spark instead of a succession of sparks, such as those produced by the ordinary form of vibrator.

A further object is to provide means by which the core of the coil may be thoroughly magnetized before the break occurs.

Other objects and advantages will appear in the following specification and the novel features of the device will be particularly pointed out in the appended claims.

Our invention is illustrated in the accompanying drawings in which—

Figure 1 is a view showing the circuits, part of the induction coil being shown in section. Fig. 2 is a sectional view of part of the coil showing the armature in its shifted position. Fig. 3 is a plan view of the plate and spring, and Fig. 4 is a plan view of the insulating block.

In carrying out our invention we provide a frame to which are secured the coils B and C, the insulating block D and the brass plate E. Each of the coils has a primary of coarse wire, shown at b' and c' respectively. These primary coils are arranged in series as shown in Fig. 1. The coil B has a secondary b² and the coil C a shunt winding c² of fine wire and relatively high resistance. The insulating block D is provided with the contact pieces d' and d², which are held by the binding screws d³ and d⁴, respectively. The core c of the coil C projects through the insulating block D, its end being covered by a felt cushion x.

Secured to the frame above the block D is the plate E. This is provided with a spring e having a tongue e' punched therefrom.

The latter has a contact point e² at its end and another e³ at its central part while the free end of the spring e bears the armature J. A felt cushion y is secured to the underside of the plate E. The battery F, the timer G, the condensers H and I and the spark plug K complete the apparatus. The parts are connected up as shown in Fig. 1.

The operation of the device is as follows. Starting at the positive pole of the battery F the current flows through the conductor 1, the plate E, spring e, tongue e', contacts e² and d² which are normally together, d³, through primary winding b' on coil B, main winding c' on coil C, conductor 2, timer G on the engine shaft and to battery through wire 3. The magnet c pulls down armature J until contacts e² and d² come together, shunting a small amount of current through the high resistance winding e² which assists in pulling the armature still lower down. The contact d² now forms a fulcrum for the tongue e' of the spring e which lifts contact e² away from d² (as the armature J goes farther down) and breaks the primary circuit. The induced current in the secondary winding b² causes the spark to jump at the plug K. The purpose of the condenser I, which is in the secondary circuit, is to augment the spark. The current still continues, however, through the shunt winding c² and the armature J is therefore held down until the contact g on the timer G has passed its spring g'. This current is so small that the spark at the timer does not burn away these contacts. As soon as the contact g leaves the spring g' the armature J returns to its normal position.

The felt cushions x and y deaden the sound of the striking of the armature. The device will work equally as well by disconnecting the high resistance winding c² on the magnet C.

We claim—

1. In a sparking mechanism, an induction device comprising a transformer coil, an electro-magnet, a spring provided with an armature and having an integral tongue bearing a pair of contacts, an insulated block having a pair of contacts arranged to be engaged by the respective contacts on said tongue, one of the contacts on said block and said tongue being in normal engagement, and the other contacts being adapted to be brought into engagement by the movement of the armature toward the magnet and to

act as a fulcrum to separate the first-named contacts.

2. In a sparking mechanism, an induction device comprising an armature coil, an electro-magnet, a supporting plate, a spring secured thereto and provided with an armature and an integral tongue, a contact at the end of the tongue and one at the center, an insulating block provided with contacts arranged to engage the respective contacts on said tongue, one of the contacts on the tongue and on the block being normally in engagement to complete the circuit through the primary of the transformer coil, and the other of said contacts being arranged to engage when the armature is attracted and to serve as a fulcrum to force the first-named contacts apart, thereby breaking the circuit through the primary and inducing a circuit in the secondary of the transformer coil.

3. In a sparking mechanism, a frame, a transformer coil secured to said frame, an insulating block carried by the frame, an electro-magnet having a core arranged to

project through said insulating block, a pair 25 of contacts carried by said block, a supporting plate secured to said frame, a spring attached to said supporting plate and having an armature and contacts arranged to engage the respective contacts on the insulating 30 block, one of said contacts serving to complete the circuit through the primary coil and the other of said contacts adapted to act as a fulcrum to move the first-named contact out of position, for breaking the current in the primary winding and thereby inducing a current in the secondary winding. 35
